COFFEE BREWER

Vincent G. Marotta, Shaker Heights, Ohio, assignor to
North American Systems, Inc., Shaker Heights, Ohio

Filed Oct. 19, 1973, Ser. No. 407,932

Term of patent 14 years

Int. Cl. D15—08

U.S. Cl. D94—3 B

FIG. 1

FIG. 2

FIG. 3

FIG. 4

FIG. 5

FIG. 1 is a front perspective view of a coffee brewer showing my new design;

FIG. 2 is a fragmentary front elevational view of the coffee brewer of FIG. 1;

FIG. 3 is a cross-sectional view along line 3—3 of FIG. 1 showing the configuration of the rear side of the coffee brewer of FIG. 1;

FIG. 4 is a side elevational view looking at the right-hand side of the coffee brewer of FIG. 1; and

FIG. 5 is a rear elevational view of the coffee brewer of FIG. 1.

I claim:

The ornamental design for a coffee brewer, as shown.
